SPECIFICATION forming part of Design No. 25,299, dated March 24, 1896.

Application filed February 24, 1896. Serial No. 580,532. Term of patent 3 $\frac{1}{2}$ years.

To all whom it may concern:

Be it known that I, ARCHIBALD F. REDDIE, a citizen of the United States, residing at the city of Philadelphia, in the county of Philadelphia and State of Pennsylvania, have invented and produced a new and original Design for Carpet or other Fabrics, of which the following, taken in connection with the accompanying drawing, is a specification.

10 The design of my invention may be applied to or wrought in Brussels, Wilton, velvet, or other carpeting in such colors and combinations of colors as may be desired, and it is best described by means of illustration. Accordingly for a description of it reference is made to the accompanying drawing, in which A is the body, B the border, and A and B the complete carpet.

15 The leading or characteristic feature of my design may be said to be the ornamental

flowers a trailing in vine or spray like fashion, and in the drawing associated with the medallions b and bands c and d, the whole being displayed upon a background e.

What I claim as new, and desire to secure 25 by Letters Patent, is—

1. In the design for a carpet the body A, substantially as shown.
2. In a design for a carpet the border B, substantially as shown.
3. The design for a carpet consisting of the body A, and the border B, substantially as shown.

In testimony whereof I have hereunto signed my name in the presence of two witnesses.

ARCHIBALD F. REDDIE.
